UNITED STATES PATENT OFFICE.

WILLIAM L. BARRON, OF NEW YORK, N. Y., AND ALBERT F. FIFIELD, OF NEWARK, NEW JERSEY, ASSIGNEES TO THE SINGER MANUFACTURING COMPANY, A CORPORATION OF NEW JERSEY.

ARTICLE-ATTACHING MACHINE.

1,354,794.

Specification of Letters Patent.

Patented Oct. 5, 1920.

Application filed April 19, 1916. Serial No. 92,136.

To all whom it may concern:

Be it known that we, WILLIAM L. BARRON and ALBERT F. FIFIELD, citizens of the United States, residing, respectively, at 5 New York, in the county of New York and State of New York, and Newark, in the county of Essex and State of New Jersey, have invented certain new and useful Improvements in Article-Attaching Machines, of which the following is a specification, reference being had therein to the accompanying drawings.

In attaching the well-known garment-hooks to fabric material of various kinds it 15 is customary to apply fastening means to the fabric across the hook-shank at the bottom of the throat and additional fastening means through the usual eyes, the purpose being to fixedly secure the hook in position 20 adjacent its longitudinal extremities and prevent displacement thereof relative to the fabric. In practice, particularly when a machine is utilized, it is difficult to apply the fastening means at the bottom of the 25 throat for the reason that the overhanging hook-bill interferes with the movement of the fastening means to final position closely embracing the hook-shank.

It has heretofore been customary to hold 30 the hook in attaching position with its back against the fabric and then to pass fastening means, in the form of ordinary stitches of thread, across the hook near the bottom of the throat and through the fabric, deflecting the thread around the end of the 35 hook-bill and into the throat as each stitch is drawn down to final position. In constructing a machine for this work it is particularly difficult to provide means for deflecting the needle-thread around the end 40 of the hook-bill with certainty and without breaking the thread, especially when sewing on hooks of the larger sizes having long bills.

45 It has also been proposed to lay a first group of fastening stitches across the hook-shank immediately behind the eyes and then relatively move the fabric and hook to slip the group of stitches to final position 50 at the bottom of the throat before passing a second group of stitches through the eyes. The disadvantage of this method, however,

is that the first group of stitches must be loosely formed in order that they may subsequently be slipped over the "hump" usually found in the shank of a garment hook opposite the end of the bill. 55

One of the objects of the present invention is to provide a machine for carrying into effect the method of attaching articles 60 to fabrics described and claimed in the application of W. L. Barron, Serial No. 127,374, filed October 24, 1916; the present machine preferably having a reciprocating fastening inserting element and article 65 holding means coöperating therewith to hold an article in a plurality of angularly relating attaching positions, so that the fastening means may be applied in different directions relatively to the article, as its 70 peculiar shape may require. More specifically, the invention has for an object to provide a sewing machine comprising a reciprocating needle and a work-holder having relative lateral jogging movements, the 75 work-holder including means for holding a garment hook in a substantially vertical position adjacent the fabric, with its throat opening upwardly, so that the needle may pass a group of stitches directly into the 80 throat of the hook. A further object is to provide means for subsequently turning the hook, so that it will lie flat against the fabric, preparatory to the application of a second group of fastening stitches through the 85 eyes of the hook. A further object of the invention is to provide means for shifting an article or hook, improperly positioned in the holder, to a predetermined correct position relative to said holder. Further objects of the invention will appear from the 90 following description and claims.

In its preferred form, the improvement is embodied in a sewing machine of the type disclosed in the patent to J. J. Sullivan, No. 95 777,564, dated December 13, 1904, which comprises a rectilinearly reciprocating fastener inserting element in the form of an eye-pointed needle operating in conjunction 100 with a work-holder to which is imparted lateral jogging movements for the production of a group of fastening-stitches and lateral movements at the completion of the first group of fastening-stitches to position the

work for reception of a second group of fastening-stitches.

As the invention in its preferred form contemplates holding a garment hook in 5 sewing position with the bend therein in contact with, or closely adjacent, the fabric and with the throat opening upwardly, a pair of special clamping-jaws are provided. These jaws are grooved to grip the side 10 edges of the bill of the hook without obstructing the throat, and are adapted to turn in the presser-members of a work-clamp of the type disclosed in the said Sullivan patent. These special jaws are mounted 15 with their axes substantially in alignment and have an offset pin-and-socket connection between them so that turning movements of one jaw will be imparted to the other, in order that a hook gripped by these 20 jaws may be turned from a vertical position to a horizontal position with its back flat against the fabric.

The usual actuating connections extend from the work-clamp to a controlling cam-wheel, which is provided with suitable cam-tracks to impart the lateral jogging movements to the work-clamp and this wheel is also made use of in the present instance to impart turning movements to the hook-clamping jaws at the proper times during 30 the sewing operation. Provision is made for arresting the motion of the work-holder during the formation of the usual tying stitches near the end of the sewing operation, and 35 thread-cutting mechanism such as disclosed in the United States patent to Horton, No. 807,676, dated December 10, 1905, is provided to sever the thread so that the work may be readily withdrawn at the end of a 40 stitching cycle.

In the accompanying drawings, Figure 1 is a side elevation of an article attaching sewing machine of the well-known Singer type embodying the present invention. Fig. 45 2 is a perspective view of the work-holder forming a part of the machine illustrated in Fig. 1. Fig. 2^a is a plan view of the work-supporting plate and hook-clamping jaws in their relative positions during the first stage 50 of the sewing operation. Fig. 3 is a bottom plan view of the work-holder shown in Fig. 2. Figs. 4 and 5 are side elevations showing two extreme positions of a certain connection at the rear of the work-clamp shown in 55 Fig. 1. Fig. 6 is a perspective of the rear end of the work-clamp illustrated in Figs. 4 and 5. Fig. 7 is a detail view of the hook-clamping jaws and the supporting means therefor. Fig. 8 is a perspective of the 60 clamp operating cam-plate shown in Fig. 3. Fig. 9 is a perspective view showing the relative positions of the needle and hook as the needle-point penetrates the fabric, preparatory to the formation of the first stitch. 65 Fig. 10 is a perspective view showing the

relative positions of the needle and work during the first stage of the sewing operation. Fig. 11 is a side elevation, partly in section, showing the needle and hook-clamping jaws, in the position shown in Figs. 2^a 70 and 10. Fig. 12 is a perspective view showing the relative positions of the needle and work during the second stage of the sewing operation, and Fig. 13 is a plan view of the completed article as attached to the 75 fabric.

In the preferred embodiment of the invention, as illustrated, the machine frame comprises a flat bed-plate 1 upon which is mounted the usual bracket-arm 2. The main-shaft 3 is journaled in the bracket-arm 2 and provided at its forward end with the take-up cam cylinder 4 having the usual crank-pin connected by means of the pitman 5 with a lateral stud upon the needle-bar 6 85 which carries a fastener inserting element in the form of the eye-pointed needle 7 coöperating with the shuttle 8, mounted in the shuttle race 9, to form a stitch and secure it in position in a manner well-known. 90

Sustained upon the sewing machine bed-plate 1 is the slide-bar 10 which carries the work-clamping instrumentalities to be hereinafter described. Jogging movements laterally of the needle are imparted to this 95 slide-bar and to the work-clamp through well-known link and lever connections comprising a link 10^a connecting the slide-bar to a bellcrank-lever 10^b, which is rocked by a link 10^c connected to the lower end of a vertical lever 10^d carrying a cam-roll positioned in a cam-groove 11 in the outer face of cam-wheel 12 mounted on the shaft 13 which also carries the usual worm-wheel 14 driven by the worm 15 on the main-shaft 3. The slide-bar 10 is given a further fastener-positioning movement laterally of the needle at the completion of a group of fastening-strokes to position the work for reception of another group of fastening strokes by the 100 usual connections in the form of a pin 16 rigidly mounted at the rear end of the slide-bar 10 and carrying a block 17 vertically adjustable thereon and received within the slotted arm 18 of a rock-lever, another arm 110 19 of which carries a cam-roll 20 running in the cam-groove 21 in the inner face of cam-wheel 12 in a manner well-known. 115

The main-shaft 3 carries at its rearward end the usual fast and loose pulleys 22 and 23 respectively, the former being provided with the stopping cam 24 which coöperates with the upper end of the stop bolt 25 slidingly mounted in the stop lever 26, fulcrumed in a manner well-known in the 125 bearing-boss 27 extended back from the bracket-arm 2. This stop-lever 26 carries the usual belt shifting device 28 and is thrown forward to start the machine by the bellcrank-lever 29 connected to an oper- 130

ating treadle (not shown) by a treadle-rod 30.

Secured upon the forward end of the slide-bar 10, by means of the usual dowel pins 31 and the screw-stud 32 is the fabric supporting plate 33 provided with a centrally disposed raised portion 34 having a flat fabric supporting surface and provided with a substantially rectangular needle aperture 35. Extending forwardly from the rear edge of the aperture 35 is a short hook supporting projection 35', the function of which will be hereinafter described. Mounted near the rearward end of the slide-bar 10 is the block 36 recessed to slidably receive the reduced and down-turned end portion 37 of the upper work-clamp arm 38. The lower edge of the down-turned end portion 37 is fitted in a transverse groove 40, Fig. 6, formed in the rearward end of an adjustable plate 41, the forward end of which is held against lateral displacement on the slide-bar 10 by a screw 42, Fig. 2, passing through a slot 42' in the plate 41. The arm 38 is capable of limited upward movement and is pressed normally toward the slide-bar 10 by the usual slightly arched, leaf-spring 52 rigidly secured to the block 36 by a screw-bolt 53 and forked at its forward end to embrace a lug 54 carried by the upper clamp-arm 38.

In order to readily effect adjustments of the upper clamp-arm 38 longitudinally of the slide-bar 10, the plate 41 is provided intermediate its ends with a rectangular opening 43, Fig. 3, in which is fitted an eccentric 44 carried by an adjusting lever 45, pivoted at one end to the slide-bar 10 by a stud-screw 46, and carrying at its free end a clamping-block 47 recessed, as shown in Fig. 2, to receive a segmental plate 48 secured to the slide-bar 10 by a screw 49. One end of the clamping-block 47 is loosely secured to the adjusting lever 45 by a screw 50 and the other end is secured to the lever 45 by a thumb-screw 51 which, when tightened, causes the clamping-block 47 and lever 45 to grip the segmental plate 48, thus holding the lever 45 in adjusted position.

The combined hook and fabric clamping levers 56, 57 are pivotally mounted beneath the forward end portion of the upper clamp-arm 38 by means of the fulcrum-studs 55 and carry at their down-turned forward ends the fabric clamping members or presser-feet 58, 59 which are adapted to clamp the fabric against the supporting plate 33 at each side of the raised portion 34. The clamping-feet 58, 59, Fig. 7, are provided with substantially aligned transverse bores 60, 61 in which are journaled the cylindrical shanks 62, 63 respectively, of the special hook clamping-jaws 64, 65. The shank 63 of jaw 65 is held in the bearing 66 provided in the clamping-foot 59 by a screw

66, while the shank 62 of the companion jaw 64 is held in its bearing in the clamping-foot 58 by the hub of a crank-arm 67 which surrounds the projecting end of shank 62 and is secured thereto by a pin 68. The jaws 64, 65 have opposed faces 69 grooved at 70 to grip the lateral edges of a hook-bill. These grooves 70 are disposed slightly to one side of the substantially aligned axes of the shanks 62, 63 and have curved end 75 portions 70' in which the bend of the hook is adapted to be seated so that when the jaws are rotated, the hook gripped thereby will turn about an axis passing very nearly through the center of curvature of the bend, 80 as shown in Figs. 10 and 11. In order that turning movements imparted to the clamping jaw 64 will be transmitted to the companion jaw 65, the jaw 64 is provided with a slightly tapered pin 71 offset from and parallel to the axis of the shank 62. A cylindrical socket 72 is provided in jaw 65 to receive the pin 71. The jaws 64, 65 are recessed at 64', 65', respectively, to provide clearance for the needle during the first 90 stage of the sewing operation as shown best in Fig. 10.

To effect the hook gripping and releasing movements of the levers 56, 57, they are provided with downwardly projecting pins 73 95 which are slidably received in oppositely inclined cam-slots 74 in a cam-plate secured by a screw 76 to a supporting-bar 77 disposed between the levers 56, 57 and slidably secured to the forward end portion of the 100 upper clamp-arm 38 by spaced screws 78, 79 received in a longitudinally extending slot 80 in said clamp-arm. It is desirable that a garment-hook be yieldingly gripped by the jaws 64, 65 and to effect this result 105 a tension-spring 81 is secured at one end to the screw 78 and at the opposite end to a vertically extending post 82 fixed to the upper clamp-arm 38.

To provide for the lifting of the upper 110 clamp-arm 38 and the parts sustained thereby for permitting insertion and removal of the work, the upper end portion of the post 82 is bent forwardly to hook over a rearwardly projecting block 83 secured to the 115 lower end of the usual lifting bar 84, adapted to be raised by the treadle-operated lever 85 in a manner well-known.

To provide for a separation of the jaws 64, 65 at the same time the clamping feet 120 58, 59 are raised from the fabric, a bell-crank-lever 86 is fulcrumed on a bracket 87 secured to the upper clamp-arm 38 in such a position that the arm 86^a of the bellcrank-lever extends downwardly in front of and 125 rests against the side of the screw 79 which is supported by the slide-bar 77 previously described. The other arm 86^b of the bell-crank lever extends forwardly beneath the down-turned free end of a fixed stop-arm 88 130

rigidly sustained in the lower end of the machine head just behind the needle-bar as shown in Fig. 1. As the clamp-arm 38 is lifted, the forwardly extended arm 86^b of the bellcrank-lever 86 will react against the fixed stop-arm 88, thus causing the arm 86^a to force the cam-plate 75 rearwardly, as shown in Figs. 2 and 8. Referring now to Fig. 3 it will be seen that such movement of cam-plate 75 will force the pins 73 outwardly and cause separation of the hook-clamping jaws 64, 65.

To effect properly timed turning movements of the hook-clamping jaws 64, 65 in their respective bearings in the fabric-clamping feet 58, 59, the crank-arm 67 previously described is connected by a screw to the front section 89^a of a two part link 89, the rearward section 89^b of which is secured by a screw 90 to the upper end of a short lever 91, the lower end of which is formed with a lateral hub 92 fulcrumed on the screw-pin 93 rigidly sustained by the plate 94 fitted in the grooved side-face of the block 36 and secured thereto by a screw 95. The link 89 is adjustable in length, the two sections thereof being secured together by a thumb-screw 96 extending through a slot 97, Fig. 3, in the section 89^a and threaded into the section 89^b. A longitudinally extending rib 98 on the section 89^b, fitted into a corresponding groove in section 89^a, assists in holding the sections in substantial alignment.

Secured to a laterally projecting seat 99, Fig. 6, intermediate the ends of the lever 91, by means of a screw 100, is the lower end of a T-shaped plate 101 the upper broadened end portion of which is provided with a slot 40 102, in the form of a flattened V, adapted to receive an actuating pin 103 on the lower end of a bellcrank-lever 104, mounted on the fulcrum-stud 105, sustained by the bracket-arm 2 in such a position that the arms thereof 45 may be acted upon in succession by projection 106 on the cylindrical surface of the cam-wheel 12 which surface acts to limit rocking movements of the bellcrank 104 in opposite directions, as shown in Fig. 1. The V-shaped slot 102 has a semi-cylindrical depression 102^a at the lower apex thereof, in which the pin 103 is partially received when the parts are in the position shown in Fig. 1. A stop-arm 107 secured to the block 36 50 by a screw 108 limits the forward movement of the lever 91, the rearward movement of which is arrested in the position shown in Fig. 4, by the upper edge of the slot 102 engaging the pin 103 on lever 104 60 which at this time is pressed against the periphery of the cam-wheel 12.

A link 109, Fig. 1, secured at one end to the lower arm of the bellcrank-lever 104 and at the other end to a manually operated lever 110 fulcrumed at 111 to a bracket 112

secured to the machine head by screws 113, permits the lever 104 to be rocked manually in order to turn the hook-clamping jaws to an inclined position facilitating the insertion of a garment-hook preparatory to a 70 sewing operation. During this manual turning operation the slide-bar 10 of the work-clamp is in starting position as shown in Fig. 1 and the pin 103 remains in the depression 102 above described. A finger 114 75 pivotally connected at its upper end by a screw 115 to the lower end of the bellcrank-lever 104, is provided with a pointed lower end 116 received in a groove in the upwardly urged free end of a leaf-spring 80 117 secured to the frame by a screw 118. From an inspection of Figs. 4 and 5 it will be clear that the spring 117 acts through the finger 114 to urge the hook-clamp rotating connections to one or the other of their extreme positions.

In the operation of the machine, after the hook and fabric have been inserted, the manually operated lever-arm 110 is pressed backwardly to turn the hook-clamping jaws 90 to the position shown in Fig. 9. The machine is then started and the needle penetrates the fabric at the point indicated by the needle 7 in Fig. 9 for the purpose of fastening the free end of the needle-thread. 95 After the needle-point has risen above the fabric and before the second penetration thereof, the projection 106 strikes the arm 104^x of the bellcrank-lever 104 and moves the pin 103 rearwardly. At the same time 100 the cam-groove 21 acts through the usual connections to bodily move the fabric-clamp forwardly, in order to position the hook-clamping jaws so that their alined axes will substantially intersect the path of movement of the needle, as shown in Figs. 10 and 11. As a result of these simultaneous movements in opposite directions, the lever 91 will be tilted rearwardly to the position shown in Fig. 4 and caused to draw the link 110 89 rearwardly and turn the hook-clamping jaws to the position shown in Figs. 10 and 11, in which position the grooves 70 are seen to be substantially parallel with the needle so that the hook is held with its throat directed upwardly. If, through the fault of the operator, the hook-bill is not properly positioned in the clamping grooves 70 with its bend seated in the curved end portions 70' of grooves 70, so as to lie substantially 115 concentric to the axis of rotation of the jaws 64, 65, the raised surface 34 and projection 35' thereof will be struck through the fabric by the bend of the hook as it turns to the position shown in Fig. 10 and will cause the 120 hook-bill to slide along the clamping-grooves 70 into proper position wherein it is supported from below by the projection 35'. It is to be understood that the projection 35' is very short so as not to catch the under 130

thread and prevent its being drawn up to the fabric. The work-holder now receives the usual lateral jogging movements through connections with the cam-slot 11 and the 5 needle lays a group of fastening stitches *b* across the hook-shank at the bottom of the throat, passing the thread directly into the throat as will be readily understood.

After a predetermined even number of 10 stitches has been formed at *b* and as the needle leaves the work, the cam 106 will have turned to a position to strike the projection 104' on the bellcrank-lever 104 and move the pin 103 forwardly along the slot 102 in plate 101. 15 At the same time the slide-bar 10 carrying block 36 is moved rearwardly with the result that the fabric-clamp and hook-clamping jaws are returned to the position shown in Figs. 1 and 9, thereby turning the hook 20 about the stitches *b* as a hinge, whereupon the needle lays a stitch *c* parallel with the first stitch *a*. As the needle leaves the fabric after laying the stitch *c*, the slide-bar 10 is retracted from the position shown in Fig. 25 1 to that shown in Fig. 5; the right hand portion of the V-shaped slot in plate 101 sliding over the pin 103 held stationary by the cam 106 in contact with the projection 104' on the bellcrank-lever 104. With the 30 hook now positioned relatively to the needle, as shown in Fig. 12, the work-clamp is given another series of lateral jogging movements as the needle passes a group of fastening stitches *d* through the eyes of the hook. 35 After the last stitch of the group *d* has been completed at the point *e*, the work-clamp is shifted to starting position, shown in Fig. 9, where the needle makes three penetrations to form two tying stitches adjacent 40 to the under face of the fabric in the manner disclosed in the Sullivan patent referred to. The stop-motion and automatic thread-cutter mechanisms with which the machine is pref- 45 ably provided are now automatically tripped into operation to stop the machine and sever the thread, whereupon the finished work may be removed.

The various adjustable elements previously described, to wit: the adjustable link 89, the 50 longitudinally adjustable upper clamp-arm 38 and the adjustable block 17, are provided for the purpose of enabling the machine to sew on hooks of the various commercial sizes. Suitable guide marks may be applied to 55 these parts so that the preliminary adjustments for a hook of given size may be quickly made.

It is to be understood that, while we have 60 shown and described the present improvement as embodied in a sewing machine, it is within the purview of the invention to utilize other types of fastener-applying mechanism. The desired relative fastener-positioning movements of the work-holding 65 means and fastener-inserting means may be

secured by imparting movements to either or both of said means, as will be readily understood. The invention is not, therefore to be considered as limited to the specific construction shown and described, as various 70 changes in the form, construction and arrangement of parts may be made without departing from the spirit of the invention. The term "fabric" as used herein is to be given its broad meaning and is not intended 75 to be limited to cloth.

Having thus set forth the nature of the invention, what we claim herein is:—

1. In an article attaching machine, in combination, means for holding an article 80 in a predetermined attaching position relatively to a body-fabric, and fastening inserting mechanism for securing the article at one point to the fabric, said article holding means being rotatable to turn the article 85 about its point of attachment as a hinge to a different position relatively to the fabric, whereby additional fastening means may be applied to fix the article to the fabric. 90

2. In a garment-hook attaching machine, in combination, means for holding a garment hook with its bend adjacent the fabric and with its throat directed at an angle to the fabric, and a device for inserting fas- 95 tening means into the throat of the hook and into the fabric.

3. In a sewing machine, the combination with stitch-forming mechanism including a reciprocating needle, of a fabric support, 100 and means for holding a garment hook with its bend adjacent the fabric and with its throat extending substantially in the direction of reciprocation of said needle, whereby fastening stitches may be passed directly 105 into the throat of the hook and into the fabric.

4. In an article attaching machine, in combination, means for holding a garment hook with its bend adjacent the fabric and with its throat directed at an angle to the fabric, and a device for inserting fastening 110 means into the throat of the hook and into the fabric, said hook holding means being shiftable to subsequently lay the back of 115 the hook against the fabric, whereby additional fastening means may be passed through the eyes of the hook and into the fabric.

5. In a sewing machine, the combination with stitch-forming mechanism including a reciprocating needle, of a fabric support, and means for holding a garment hook with its bend adjacent the fabric and with its throat extending substantially in the direction of reciprocation of said needle, whereby fastening stitches may be passed directly 120 into the throat of the hook and into the fabric, said hook holding means being shift- 125 able to subsequently lay the back of the 130

hook against the fabric, whereby additional fastening means may be passed through the eyes of the hook and into the fabric.

6. In a machine for sewing on garment hooks, or the like, the combination with fastening inserting mechanism, of a fabric support, gripping means for holding a garment-hook with its bend adjacent the fabric and its throat directed at an angle to the fabric for reception of a fastening, and means for rotating said gripping means to lay the back of the hook against the fabric for reception of an additional fastening.

7. An article attaching machine comprising, in combination, fastening inserting means including a reciprocating element, fabric supporting means, mechanism for producing relative lateral movements of said reciprocating element and said fabric-supporting means, and article-holding means mounted for turning movements about an axis extending transversely of and closely adjacent the path of reciprocatory movement of said element, whereby an article may be held in different attaching positions relative to the fabric during the attaching operation.

8. An article attaching sewing machine comprising, in combination, stitch-forming mechanism including a reciprocating needle, fabric supporting means, mechanism for producing relative jogging movements of said reciprocating needle and said fabric supporting means, and article holding means mounted for turning movements about an axis closely adjacent and extending transversely of the path of reciprocatory movement of said needle.

9. In an article attaching machine, the combination with fastening attaching means including a reciprocating fastening inserting element, fabric clamping members, and article clamping members pivotally mounted for turning movements relative to said fabric clamping members about an axis extending transversely of the direction of reciprocatory movements of said fastening inserting element.

10. In a machine for sewing on garment hooks or the like, the combination with stitch-forming mechanism including a reciprocating needle, and fabric-clamping means, said stitch-forming mechanism and fabric-clamping means having relative stitch-positioning movements laterally of the needle, of hook-holding means mounted for turning movements about an axis extending transversely of and closely adjacent the path of reciprocatory movement of the needle, whereby the hook may be held in different attaching positions relative to the fabric.

11. In a sewing machine, in combination, stitch-forming mechanism including a re-

ciprocating needle, a fabric-support, means for producing relative lateral jogging movements of said needle and support, and rotatably mounted means for holding a garment-hook in different positions relative to the fabric during the sewing operation.

12. In a machine for sewing on garment-hooks or the like, the combination with stitch-forming mechanism including a reciprocating needle, a fabric-clamp, and means for producing relative lateral jogging movements of said needle and clamp, of garment-hook clamping elements mounted for turning movements relative to said fabric-clamp whereby a hook may be held in different positions relative to the fabric during the sewing operation.

13. In a machine for sewing on garment-hooks or the like, the combination with stitch-forming mechanism, of a fabric-clamping means, garment-hook clamping elements, and means for imparting to said garment-hook clamping elements movements of rotation relatively to said fabric-clamping means during the sewing operation.

14. In a sewing machine, in combination, stitch-forming mechanism including a reciprocating needle, a fabric-support, means for producing relative lateral jogging movements of said needle and fabric-support, article-holding means pivotally mounted on an axis extending transversely of the direction of reciprocatory movement of the needle, and means for imparting to said article-holding means turning movements about said axis.

15. In a sewing machine, in combination, stitch-forming mechanism including a reciprocating needle, a fabric-support, means for producing relative lateral jogging movements of said needle and fabric-support, article-holding means pivotally mounted on an axis extending transversely of the direction of reciprocatory movement of the needle, and automatically operated means for imparting to said article-holding means turning movements about said axis.

16. In a sewing machine, in combination, a main-shaft, stitch-forming mechanism including a reciprocating needle actuated by said shaft, a work-holder including pivotally mounted article-holding means, and means driven by said shaft for bodily moving said article-holding means laterally of the needle and imparting turning movements thereto, during the sewing operation.

17. In a sewing machine, in combination, stitch-forming mechanism including a reciprocating needle, a fabric-holder having the plane of its fabric-supporting surface intersected by the path of movement of said needle, and article-holding elements pivotally mounted on an axis extending trans-

versely of the needle and disposed directly above said surface.

18. In a sewing machine, in combination, 5 stitch-forming mechanism including a reciprocating needle, a fabric-holder having a fabric-supporting surface intersected by the path of movement of said needle, and article-holding elements pivotally mounted on an axis substantially parallel with and disposed directly above said surface.

19. In a sewing machine, in combination, 10 stitch-forming mechanism including a reciprocating needle, a fabric-holder having a fabric-supporting surface intersected by the path of movement of said needle, and article-holding elements pivotally mounted on an axis substantially intersecting the path of movement of the needle.

20. In a sewing machine, in combination, 15 stitch-forming mechanism including a reciprocating needle, article-holding means pivotally mounted on an axis extending transversely of and substantially intersecting the needle-path, and means for producing relative jogging movements of said needle and article-holding means laterally of said needle and longitudinally of said axis.

21. In a sewing machine, in combination, 20 stitch-forming mechanism including a reciprocating needle, a fabric-support, garment-hook clamping members having opposed hook-engaging grooves extending in the same general direction as the needle and adapted to support a garment-hook with its 25 throat opening upwardly, and means for producing relative lateral jogging movements of said needle and clamping members whereby stitches will be laid directly into the throat of said hook.

22. In a garment-hook sewing machine, 30 the combination with a reciprocating needle, a vibrating work-clamp and operating means therefor including a cam-wheel, hook clamping jaws pivotally mounted upon said 35 work-clamp, a lever pivotally mounted adjacent the periphery of said cam-wheel and connected to turn said jaws on their pivots and means on said cam-wheel for moving said lever first in one direction and subsequently in the opposite direction.

23. In a sewing machine, in combination, 40 a frame, a work-holder mounted on said frame and comprising a fabric supporting member and a downwardly spring-pressed 45 presser-member including spaced reciprocally movable article-gripping jaws mounted to swing about substantially vertical axes as they grip or release an article, means for lifting said presser-member, a stop carried by said frame, and a device reacting against said stop to separate said clamping jaws when said presser-member is lifted.

24. In a sewing machine, in combination, 45 a frame, a work-holder mounted on said

frame and comprising a fabric-supporting 65 member and a downwardly spring-pressed presser-member, said presser-member including a pair of spaced article-gripping jaws, a controller element, and connections between said controller element and said 70 article-gripping jaws for moving the latter simultaneously in opposite directions to grip or release an article, means for lifting said presser-member, a stop carried by the frame, and a device reacting against said stop to 75 shift said controller element and separate said clamping jaws when said presser-member is lifted.

25. Work-holding mechanism for sewing machines comprising a frame, a work-supporting member having a work-sustaining face, an article-holding member constructed with a support, a pair of reciprocally movable levers mounted on said support and provided with laterally spaced article-clamping jaws, means for lifting said support, a stop carried by the frame, and a lever sustained by said article-holding member and adapted to separate said jaws, said stop being positioned in the path of movement of said lever, whereby the article-clamping jaws will be separated as said article-holding member is lifted.

26. A work-holder for sewing machines 80 comprising, in combination, a fabric support, presser means opposed to said support, and article gripping means mounted for turning movements relatively to said fabric support and presser means.

27. A work-holder for sewing machines 85 comprising, in combination, a fabric-supporting plate, supporting members opposed to said plate, and article-gripping jaws mounted for turning movements in said supporting members.

28. A work-holder for sewing machines 90 comprising, in combination, a fabric-supporting plate, fabric-clamping members opposed to said plate, and article-gripping jaws mounted for turning movements in said 95 fabric-clamping members.

29. A work-holder for sewing machines comprising, in combination, a fabric-supporting plate, fabric-clamping members opposed to said plate, and article-gripping 105 jaws mounted in said clamping members for turning movements about an axis substantially parallel to said plate.

30. A work-holder for sewing machines comprising, in combination, a fabric-supporting plate, supporting members opposed to said plate, opposed article-gripping jaws having shanks journaled in said supporting members in substantial alinement, a pin-and-socket connection between said jaws eccentric to said shanks, and means for turning one of said shanks.

31. A combined fabric and article clamp

- for sewing machines comprising, a lower fabric support, clamping means mounted for movements toward and from said support, and article-holding means rotatably mounted 5 on said clamping means.
32. A combined fabric and article clamp for sewing machines comprising, a lower fabric support having a substantially flat fabric-supporting face, clamping means 10 mounted for movement toward and from said support, and article-holding means mounted on said clamping means to turn about an axis substantially parallel with said fabric support.
33. A work-holder for sewing machines comprising, in combination, a main-shaft, a fabric-clamp, article-gripping means rotatably mounted therein, connections between said main-shaft and said article-gripping 20 means for imparting turning movements thereto, and manually operated means for turning said gripping means.
34. In a sewing machine, in combination, a main-shaft, a fabric-clamp, article-gripping means rotatably mounted therein, lost-motion connections between said main-shaft and said article-gripping means for imparting turning movements thereto, and manually operated means acting through said 30 connections to turn said gripping means.
35. A work-holder for sewing machines comprising, in combination, a fabric-supporting plate, clamping members opposed to said plate, article-clamping means rotatably 35 supported by said clamping members, actuating means, and connections between said actuating means and said fabric and article-clamping means for bodily moving said fabric-clamp and turning said article-clamping 40 means.
36. An article-clamp for sewing machines comprising, in combination, pivotally mounted article-clamping means, devices for determining the limits of turning movements 45 of said article-clamping means in opposite directions, means for imparting turning movements to said article-clamping means, and a spring-actuated device for urging said article-clamping means to each of the extreme 50 positions thereof.
37. An article-attaching sewing machine comprising, in combination, stitch-forming mechanism, a work-holder, means for producing relative lateral jogging movements 55 between the stitch-forming mechanism and work-holder, and means acting automatically during the stitching operation to shift an article improperly positioned in said holder to a predetermined position relative thereto and to the stitch-forming mechanism. 60
38. In an article-attaching sewing machine, a work-holder including a rotatably mounted article holding device, and means acting as said device is rotated to correctly 65 position an article improperly situated in said device.
39. In an article attaching sewing machine, a work-holder including a rotatably mounted article holding device, and a stop 70 acting as said device is rotated to correctly position an article improperly situated in said device.
40. In a machine for sewing on garment hooks, a work-holder including a fabric supporting plate, article gripping jaws movably mounted above said plate, and means carried by said plate for shifting a hook improperly held by said jaws to a predetermined correct position relative to said jaws. 75
41. In an article-attaching sewing machine, a work-holder including opposed hook holding elements, work-holder actuating means and means acting during the actuation of said work-holder to shift a hook incorrectly positioned between said hook-holding elements to a predetermined correct position relative thereto. 80
42. A sewing machine comprising stitch forming means, and a work holder having 90 means to sustain a hook with its shank approximately parallel with the path of the needle.
43. A sewing machine comprising stitch forming means, and a work holder having 95 movable means to sustain a hook with its shank approximately parallel with the path of the needle.
44. A sewing machine comprising stitch forming means, a work holder having movable means to sustain a hook with its shank approximately parallel with the path of the needle, and means to effect movement of said hook to bring its shank to an angle with 100 said needle path. 105
45. A sewing machine comprising stitch-forming means, a work-holder movably mounted, a swinging hook carrier mounted on said work-holder, means for moving said work-holder and means for effecting swinging movement of said hook carrier during a movement of said work-holder whereby to change the angle of a hook in said carrier relative to the stitch-forming devices. 110
- In testimony whereof we have signed our 115 names to this specification.
- WILLIAM L. BARRON.
ALBERT F. FIFIEND.
